UNITED STATES PATENT OFFICE

JULIUS GIESECKE AND HERMANN GIESECKE, OF LEIPZIG, GERMANY

MIRROR DISPLAYING DEVICE

Application filed May 17, 1930, Serial No. 453,268, and in Germany December 17, 1928.

This invention relates to an amusement apparatus and consists in the provision of a cabinet containing a plurality of differently distorting mirrors and means for displaying such mirrors in succession. The mechanism may be normally locked and adapted to be released on the insertion of a coin.

Fig. 1 of the accompanying drawings represents a front view of the mechanism,

10 Fig. 2 is a side view of the same,

Fig. 3 is a perspective view of the cabinet on a reduced scale, and

Fig. 4 is a view of a detail.

A suitable mounted cabinet *a* contains a 15 plurality of mirrors *b* 1-6 which are suspended one behind another on cords *c* and *d*. The mirrors are curved or corrugated in different manners, some vertically and others horizontally, so as to reflect differently distorted images for the amusement of the observer. The cords *c* and *d* are led over pulleys *e* arranged on shafts *f* in the upper part of the cabinet, and are connected at the ends to pulleys *i* and *k* arranged loosely on a shaft 20 *j* in the lower part of the cabinet. The cord *d* is led direct from the pulley *e* to the pulley *k* while the cord *c* is deflected over a pulley *h* arranged on a shaft *g*. Each mirror is controlled independently in this manner,

25 while the shafts *f*, *g*, and *j*, are common to the respective pulleys. The controlling pulleys *i* and *k* of each mirror are interconnected so that they can be employed for winding the cords and raising the mirrors from a con-

30 cealed position in the cabinet into displaying position in front of a window *m* provided in the front wall of the cabinet. For raising the mirrors the shaft *j* is provided with the rigidly secured discs each carrying a tappet *y* adapted to engage a pin *w* on a pair of pulleys *i*, *k*. A detachable crank handle *l* on the 35 shaft *j* is used for turning the latter so as to raise all the mirrors together, which is effected by one turn of the handle. Double-

40 armed catches *n*, pivoted at *o* and controlled by springs *x* are adapted to engage in notches in the pulleys *i* for retaining the latter with the mirrors in raised position, the shaft *j* being restored by a spring to its initial position as soon as it is released. For each catch,

a push button *t* is provided by the depression of which the catch can be operated for releasing the mirror. This arrangement allows the mirrors to be dropped one by one from the front rewards for displaying all the 55 mirrors in succession.

The shaft *j* carries a structure comprising two arms *u* and *v* which participate in its rotation. A bell-crank mounted on a pivot *s* has, on one arm *t*, a catch which engages the arm *t* so as to prevent the shaft *j* normally from being rotated. Another arm *t'* of the bell crank is situated under a coin chute *v* so as to intercept coins passing down the latter from a coin slot *q*. The bell crank is balanced so as to be rocked by the coin for releasing the shaft *j*, its movement being in the first place limited by abutment against the arm *u*. The shaft *j* can now be turned for raising the mirrors, and as the arm *u* turns with the shaft, it releases the bell crank so that it can turn under the weight of the coin for dropping the latter, whereupon the bell crank returns to its initial position for rearresting the shaft *j* as the latter is restored. 75

50 Buffers may be provided for reducing the shocks of the mirrors as they drop into the lower part of the cabinet, and the latter is provided with guide elements which maintain the mirrors in their proper planes. 80

The device may be modified in various manners. For instance a single push button may be employed by the depression of which the catch *n* of the first mirror, or of a screen 85 which covers the mirrors, is operated, the catches of the succeeding mirrors being formed with arms *n'*—arranged so as to be engaged by mirrors in advance thereof as said mirrors drop. In this manner the mirrors will be automatically released in succession. Means may be provided for braking the mirrors so as to retain each one in view for a sufficiently long time. 90

We claim:

1. A mirror displaying device comprising a cabinet, a plurality of differently distorting mirrors suspended from cords within said cabinet one behind another, pulleys whereon said cords can be wound for raising the 100

- mirrors together from a concealed position into displaying position, means for retaining them in displaying position, means for releasing and dropping the mirrors one by one in succession, a shaft whereon said pulleys are arranged to rotate a detachable crank handle on said shaft, and carriers connected to said shaft so as to engage the pulleys and wind the cords when the shaft is rotated in one direction.
- 10 2. A device as claimed in claim 1 wherein the mirrors are retained in raised position by catches adapted to engage in notches in said pulleys.
- 15 3. A device as claimed in claim 1 wherein the mirrors are retained in raised position by catches adapted to engage in notches in said pulleys, the releasing means consisting of a push button whereby the first catch is operated, and arms on the succeeding catches adapted to be engaged in succession by the falling mirrors so as to release their own mirrors automatically.
- 20 4. A device as claimed in claim 1 in combination with a catch normally locking said shaft, and means for releasing the shaft from said catch by the insertion of a coin into the cabinet.
